UNITED STATES PATENT OFFICE.

CHARLES R. LAMBERT, OF DETROIT, MICHIGAN, ASSIGNOR TO CLAYTON & LAMBERT MANUFACTURING COMPANY, OF DETROIT, MICHIGAN, A CORPORATION OF MICHIGAN.

FIREPOT.

1,381,924.

Specification of Letters Patent. Patented June 21, 1921.

Application filed May 4, 1918. Serial No. 232,446.

To all whom it may concern:

Be it known that I, CHARLES R. LAMBERT, a citizen of the United States of America, residing at Detroit, in the county of Wayne, 5 and State of Michigan, have invented certain new and useful Improvements in Firepots, of which the following is a specification, reference being had therein to the accompanying drawings.

10 This invention relates to sheet metal devices such as fire pots, although the invention in its broader aspects is not limited to the particular use mentioned.

One of the objects of the invention is to 15 provide a top plate section for fire pots or the like which can be formed as a stamping and which will have sufficient strength and rigidity to properly support a heavy metal pot for melting lead, solder or the like.

20 Other objects of the invention are to provide a new and improved retaining device having a sheet metal bottom ring for connecting the melting pot shield to the top plate section of the fire pot; and in general 25 to provide a new and improved top plate section, shield and retaining mechanism which can be entirely formed from sheet metal and preferably by a stamping operation.

30 The invention also resides in such other arrangements of parts and features of construction as will more fully hereinafter appear.

In the drawings:

35 Figure 1 is a side elevational view, showing a fire pot embodying my invention;

Fig. 2 is an enlarged plan view of the top plate;

40 Fig. 3 is a section on line 3—3 of Fig. 2;

Fig. 4 is a plan view of the retaining ring;

Fig. 5 is a section on line 5—5 of Fig. 4;

45 Fig. 6 is a plan view showing the retaining ring and top plate section in assembled position.

Referring to the particular construction shown in the drawings and describing first in detail the general arrangement of parts illustrated in Fig. 1, A designates a fire 50 pot having a tank or reservoir A' and a burner section B carried by the top plate C. The latter is supported from the reservoir or tank A' by means of a plurality of rods C' which at their lower ends are threaded 55 into fittings A² in the top of the tank A'

and at their upper ends are secured to lugs C² formed in the top plate. A suitable bail or handle D is provided for carrying the fire pot from place to place, this bail or handle having fittings D' which when 60 turned to their upright position interlock with inclined lugs D² carried by the top plate. The parts so far described are of old and well-known construction and in using such fire pots it is customary to provide a sheet metal shield E which is detachably carried by the top plate. This shield is of a size to receive a suitable melting pot E' which rests on the top plate in the manner hereinafter described. 65

The shield performs a further function of directing the heated gases against the outer wall of the melting pot, thus increasing the efficiency of the device. However, as it is desirable sometimes to use the top plate as an 70 open burner section means are provided for detachably securing the sheet metal shield E to the top plate. Heretofore both the top plate and the bottom ring of the metal shield have been formed from castings and the 75 present invention contemplates a novel arrangement of stamping or other sheet metal member which can be used in place of casting members. The detailed construction and arrangement of these parts are shown in 80 Figs. 2 to 6 respectively. 85

Taking up now in detail the top plate construction shown in Figs. 2 and 3, F designates the main body portion of the top plate which at its outer edge is provided with a 90 strengthening flange F' and also with lugs C² which receive the supports or uprights C'. The central portion of the main body section F is cut away at F² to permit the passage of the hot gases from the burner to the 95 interior of the melting pot shield. To strengthen the metal at the central part of the top plate the inner edges G are preferably flanged, these flanges being inclined upwardly and terminating in inwardly projecting U-shaped lugs H which form a very 100 strong and rigid support for the melting pot or other article placed on the top plate C. In addition to these lugs the top plate section has a pair of outwardly projecting lugs 105 H' and H² which are bent into cylindrical shape to receive the bail or handle lugs D². There is also a plurality of tongues I, I' and I² which are formed by striking a part of the metal of the main body portion F up- 110

wardly and then bending it outwardly to the shape shown in Figs. 2 and 3. The tongues I, I' and I² coöperate with lugs J, J' and J² formed on the sheet metal retaining ring 5 K which is secured by any suitable means to the lower end of the melting pot E'. The detail of the retaining ring for the bottom of the shield E is shown in Figs. 4 and 5. This ring comprises a flat member which is 10 bent to form an upwardly and outwardly inclined retaining flange L, the ring being then bent into circular form so that its ends M and M' meet as shown in Fig. 4. Sufficient stock is left to provide a horizontal flange 15 N from which there projects inwardly the lugs J, J' and J², previously mentioned. These lugs are provided with central recesses O which register with the tongues I, I' and I² formed in the top plate and the metal of 20 the lugs is preferably inclined upwardly from the recessed portion O so as to give a cam effect when the retaining ring on the melting pot shield is interlocked with the top plate.

In locking the shield to the top plate it is 25 only necessary to place it on the latter so that the recesses O register with the tongues I. The shield is then rotated to interlock the lugs J, J' and J² with the tongues I, I' and I². When it is desired to remove the shield 30 it is simply rotated to bring the recesses again into registration with the tongues on the top plate so that the shield can be lifted off.

While I have shown and described the invention with reference to securing a sheet metal shield to the top plate of a fire pot, it is 35 obvious that the interlocking members are capable of other uses.

What I claim as my invention is:—

In a fire pot or the like, a top plate comprising a sheet metal stamping having a central apertured portion and a flanged portion adjacent said opening, and inwardly projecting supporting lugs, said supporting lugs 45 being channel shaped in cross section.

In testimony whereof I affix my signature.
CHARLES R. LAMBERT.
